UNITED STATES PATENT OFFICE.

ALONZO GILBERT, OF STANTON, MICHIGAN.

FIFTH-WHEEL FOR VEHICLES.

SPECIFICATION forming part of Letters Patent No. 425,938, dated April 15, 1890.

Application filed February 20, 1890. Serial No. 341,220. (No model.)

To all whom it may concern:

Be it known that I, ALONZO GILBERT, a citizen of the United States, residing at Stanton, in the county of Montcalm and State of Michigan, have invented certain new and useful Improvements in Fifth-Wheels for Vehicles; and I do hereby declare the following to be a full, clear, and exact description of the invention, such as will enable others skilled in the art to 10 which it appertains to make and use the same.

My invention relates to improvements in fifth-wheels for vehicles; and the object of my invention is to simplify the construction and provide means for taking up the lost motion due to the wearing away of the parts in frictional contact; and it consists in the construction, combination, and arrangement of the parts, as hereinafter described, and more particularly pointed out in the claims, reference being had to the accompanying drawings, wherein—

Figure 1 is a vertical section of a device embodying my invention on the line xx of Fig. 2; Fig. 2, a plan of the same; Fig. 3, a detail of same with parts removed, and showing another method of applying the invention to a vehicle; Fig. 4, a detail of same device as shown in Fig. 1, with parts removed and adapted to a different form of reach; and Fig. 30 5, an end elevation of same; Fig. 6, a vertical section on same line as Fig. 1, showing still another method of applying said invention.

Like symbols of reference indicate like parts in each.

35 A represents the front axle of a vehicle; B, the wooden axle-bed placed upon the axle; C, the head-block.

D is a saddle, upon which the head-block rests and by which the upper circle-plate of 40 the fifth-wheel is secured to the head-block, and is provided with a lug E, having a conic socket and forming a conic bearing for the conic journal I. The upper circle-plate F is flanged and fits over the lower circle-plate G, and is provided with an inwardly-projecting lug F', having a socket to accommodate the boss L on the brace K' and a vertical opening for the bolt M. The lower circle-plate G is secured to the axle-bed B by means of saddle H, which is provided with a projecting lug E', having horizontally-projecting lugs for

the bolts, by which it is firmly secured to the axle-bed, as shown in Fig. 2. The lug E forms the journal I for the upper and the box for the lower cone-bearings, which constitutes the 55 essential feature of the invention and upon which the axle turns. The lower cone-journal I' is integral with brace K', which extends forward underneath the axle, and is secured to upper circle-plate F by bolt M, and has the 60 boss L and the lip O under the lower circle-plate G. Brace K connects the reach to lug E. The parts are secured in position by bolt M', and the usual reach-plates J J' may be added, if desired.

65 The various modifications of the device in its application to vehicles, as illustrated by Figs. 3, 4, 5, and 6, can be readily understood upon inspection. In Fig. 3 the cone-bearings are shown, and the bolt is placed in the rear 70 of the same for holding the parts together, the cone-bearings forming the king-bolt. In Figs. 4 and 5 the brace K' terminates in a hanger P, to which a spring-reach may be attached. In Fig. 6 the lug E is provided with a projecting lug Q, which forms a cap for the boss L' 75 at the end of the brace K'', through which passes the bolt M'', securing the parts together.

80 It is evident that in this device the lost motion due to the wearing away of the cone-bearings and the engaging surfaces of the upper and lower circles of the fifth-wheel may be taken up by simply filing or cutting down the tops of the bosses L L' and tightening the 85 nuts upon the bolts M M'', and that the usual king-bolt is dispensed with entirely. It is also evident that in the other modifications of the device shown in the other figures the lost motion will be taken up by filing off the 90 top of the boss L and shortening the brace K, or by placing a washer upon the top of the lug E and underneath the brace K. When the bolt is placed outside the pivot, the bearings may be solid—that is, the vertical aperture 95 for the bolt may be dispensed with, as shown in Figs. 3 and 6.

What I claim, and desire to secure by Letters Patent, is—

1. In a fifth-wheel for vehicles, and in combination with the circle-plates and the saddles D and H, provided with the lugs E and

E', having the conical bearing-surfaces, as set forth, the brace K', having the conic hub or journal I', the boss L, and lip O, integral and secured to the end of the reach, and the bolt 5 M', for securing the parts together, substantially as and for the purposes set forth.

2. In a fifth-wheel for vehicles, and in combination with the circle-plates and the saddles D and H, provided with the lugs E and 10 E', having the conic bearings, arranged as described, the lug Q on the lug E, the brace K'',

having the boss L', connecting the reach and lug Q, a bolt for securing the parts together, and the brace K', having the boss L and bearing I' integral, substantially as and for the 15 purpose set forth.

In testimony whereof I affix my signature in presence of two witnesses.

ALONZO GILBERT.
